APPARATUS FOR LOCKING CONTROL PLUNGERS IN SLIDE VALVE CONTROL DEVICES

Hermann Jacobi, Frankfort-on-the-Main, Germany, assignor to American Lurgi Corporation, New York, N. Y., a corporation of New York

Application September 6, 1940, Serial No. 355,703
In Germany December 1, 1938

7 Claims. (Cl. 137—139)

This invention relates to the slide valve control switch art, and is concerned with improved locking devices for the control plungers of slide valve control switches for actuating oscillating machine parts and with improved methods of locking such control plungers.

Slide valve control switches, consisting essentially of a source of energy, a control member (rotary or plunger slide valve switch), a working cylinder and an hydraulic seal, for actuating oscillating machine parts are known. In addition, it heretofore has been proposed to lock such control members.

An object of the present invention is to provide improved devices for locking control plungers, which devices will be easy to operate and whose functioning will be dependable. Another inventive object is the provision of a double-acting locking device of the general type above described. A further object of invention is the provision of an improved method of locking control plungers of slide valve control switches. Other inventive objects will be apparent from a consideration of the following description and of the appended claims.

The invention consists essentially in a new mode of locking control plungers of such switches in which the pressure of the liquid or gaseous pressure fluid effective in the working cylinder is used for locking the control plunger. After actuation of the control plunger, the pressure fluid is first led to a locking piston that in its turn holds the control plunger in the desired position, whereupon the pressure fluid is conducted into the working cylinder; after the pressure fluid has completed delivery of work force to the working piston in the working cylinder it exerts pressure on the opposite side of the double-acting locking plunger, whereupon equalization of pressure occurs at the two sides of the locking plunger permitting release of the locking member. According to the invention, a difference in pressure is produced in the circulating pressure agent by throttling the pressure fluid flowing to the working cylinder, this difference in pressure causing the engagement of a locking plunger in the locked position, whereupon, after cessation of the flow of the pressure fluid to the working cylinder, an equalization in pressure takes place automatically.

The new process for locking control plungers, and improved devices for carrying out that process, will now be explained in greater detail in connection with an illustrative constructional example and with reference to the accompanying drawings, in which:

Fig. 1 is a sectional view of the slide valve switch and the working cylinder with which it cooperates, showing the position of the control

plunger when the pressure agent is kept in circulation without delivering work;

Fig. 2 is a view similar to that in Fig. 1, and showing a working position of the control plunger; and

Fig. 3 is a similar view showing a modified form of the locking device, in which view another working position of the control plunger is shown.

The specific device illustrated by the figures of 10 the drawings is adapted for actuating swinging parts, for instance, the landing gear, of airplanes and also for actuating similar oscillating mechanisms.

The pressure fluid, for which oil or a gaseous 15 agent enters chiefly into question, is kept in constant circulation, by means of a pump 1 (which may, as is illustrated, be a gear-wheel pump), through the pipes 7 and 8, the passage opening 17, the recess 18 inside the control plunger 5, the opening 19 and the pipes 13, 14 (the latter shown partly by broken lines) and the collecting receptacle 4. The openings 17 and 19 at the same time are connected to the annular passages 17' and 19', respectively, which latter are cut as 20 grooves into the plunger 5. The pressure chamber 20 with the double-acting locking plunger 24 is connected to the annular passage 17'. The pressure on the lower plunger surface of plunger 24 is compensated, in the rest position of the control plunger 5, by a counter pressure acting on 25 the top of the locking plunger 24 through the throttle pipe, or excess pressure valve, 22 between the pipes 8 and 23, and the annular passage 23'. In addition, a spring 26 causes the locking plunger 24 carrying locking pin 25 to remain constantly 30 in the disengaged position as long as there is equalization of pressure on the two sides of the locking plunger.

By displacement of the control plunger 5 to the 35 left, as shown in Fig. 2, the circulation of pressure fluid through the opening 19 in the pipe 13 is interrupted and, instead, the pressure fluid is carried around through the constricted connecting passage 21, or by opening of the excess pressure valve 22, through the passage 23, the opening 17', the recess 18 and further the opening 32 with the annular passage 32', through the passage 9 and pipe 11 into the working cylinder 3. At the same time, the locking plunger 24 is 40 brought to the locked position by the excess pressure making its appearance in the passage 8 and the pressure chamber 20 as shown in Fig. 2. Under the conditions thus obtaining, the pressure fluid pushes the work piston to the right (in the direction of the arrow) in the working cylinder 3. 45 As soon as the work piston in the working cylinder 3 has reached the end position of its stroke, in connection with which it has forced the pressure fluid in front of it in the working cylinder through the connecting pipe 12, the pas- 50

sage 10 and the opening 15 into the pipe 16 and thereby into the collection chamber 4, there is an equalization of pressure that was not present before due to the flow of the pressure fluid through the constricted passage 21. This difference in pressure caused by the constricted passage 21 during passage of the pressure fluid produces a greater pressure on the bottom of the plunger 24 than on the top of the same, so that the locking pin 25, as is shown in Fig. 2, presses into the annular passage 17' and thereby holds the control plunger 5 in the locked position. This locked position is relinquished again at the moment when, upon attaining the end position of the work piston in the working cylinder 3, flow of the pressure fluid ceases and thereby there is regained equalization of pressure between the passages 23 and 21. Through the annular passage 17' in connection with the passage 23, under certain cases the pressure is transmitted to the top of the locking plunger 24 through the connecting passage 27 in the lock pin 25, so that at both sides of the locking plunger equalization in pressure is produced and the locking plunger 24 is, by means of spring 26, caused to become disengaged from the annular passage 23' (position Fig. 1). By the spring 28 between the annular shoulders 29, 30 at one end of the control plunger 5, the control plunger 5 is held in the mean position shown in Fig. 1 after the locking pin 25 is disengaged. In addition, the middle position of the control plunger 5 can, if desired, be assured by an additional spring rest (not shown).

The reverse working operation is accomplished upon displacement of the control plunger 5 to the right, as shown in Fig. 3. The pressure fluid, due to the excess pressure occurring in the pressure chamber 20, presses the locking plunger 24' against the control plunger 5, this locking plunger being constructed here without locking pin 25 and without spring 26, according to a modification of the invention. The locking of the control plunger 5 is accomplished here solely by the application of the locking plunger 24'. For increasing its clamping effect, special frictional surfaces can be provided on the locking plunger, or a special shape can be given the locking plunger surfaces. The clamping effect compensates the pressure of the spring 28, so that the spring 28 cannot draw the control plunger 5 back to the middle position. Thereupon, the pressure fluid flows through the excess pressure valve 22, or the constricted passage 21, through the opening 32, the recess 18, the opening 19 in the reverse direction through the passage 10 and the connection pipe 12 into the working cylinder 3 and pushes the work piston in the direction of the arrow, to the left, into its reverse end position. Upon the happening of this event, there is again reached an equalization of pressure between the pipes 8 and 23 through the constricted passage 21 and thereby an equalization of pressure at the opposed sides of the plunger 24', i. e., between the annular chamber 32' and the pressure chamber 20. The pressure agent in front of the work piston is led back through the pipes 9, 15 and 16 into the collection receptacle 4.

The structure of the locking plunger 24' without the locking pin 25 makes it possible to bring back the control plunger 5 each time by hand in overcoming the spring pressure 28, so as to interrupt the working operation in the working

cylinder 3 as desired. Finally the excess pressure valve 22 could likewise be opened by a special handle (not shown) in order to cause equalization of pressure at once and thereby to release the locking plunger 24 (or 24') from its locked position.

The locking of the control plunger according to the invention can be used, in the same way as shown here in the example of the plunger slide valve, on other slide valves likewise, for instance, rotary valves, with the same success.

I claim:

1. In a slide valve control device having a double-acting locking plunger, said locking plunger being movable into and out of locking relationship with a slidable control element by a pressure fluid, compression chambers on opposite sides of said plunger, said opposed compression chambers being separately connected with said pressure fluid, throttling means between said pressure fluid and one of said compression chambers effective upon appropriate movement of said slidable element to produce a difference in pressure of pressure fluid in the two compression chambers for moving said locking plunger into locking relationship with said device.

2. In a slide valve control device for actuating a movable machine part, of the type described, including a slidable control element, the combination comprising a double-acting locking plunger, said locking plunger being movable into and out of locking relationship with said slidable control element by a fluid pressure, a pressure fluid conduit, two opposed compression chambers on opposite sides of said plunger, each of said opposed compression chambers being separate from the other and in communication with said pressure fluid conduit, and a throttling means between said pressure fluid conduit and one of said compression chambers effective upon appropriate movement of said slidable element to produce a difference in pressure of pressure fluid in the two compression chambers for moving said locking plunger into locking relationship with said element whereupon, when said movable machine part has reached its end position, an equalization of pressure of pressure fluid is automatically effected in the two compression chambers to permit movement of said locking plunger from locking relationship with said element.

3. The combination defined in claim 2, in which the locking plunger is provided with a locking pin and the slidable control element is provided with a recess engageable by said pin.

4. The combination defined in claim 2, in which the locking plunger is provided on that side thereof adjacent the control plunger with a friction-increasing surface for engaging a surface of the locking plunger in locking relationship.

5. The combination defined in claim 2, in which a resilient member presses against one side of said locking plunger.

6. The combination defined in claim 2, in which the throttling means includes a constricted passage between said pressure fluid conduit and one of said compression chambers.

7. The combination defined in claim 2, in which the throttling means includes a passage between said pressure fluid conduit and one of said compression chambers and an excess pressure valve in said passage.

HERMANN JACOBI.
